SWIVEL BUMPER

Herbert C. Dye, Bakersfield, Calif.

Application February 3, 1936, Serial No. 62,049

6 Claims. (Cl. 255—25)

5 My invention relates to swivels employed in oil well drilling rigs, and has particular reference to a bumper or guard which may be employed upon a swivel of such character as to prevent unnecessary wear thereof, or unnecessary wear upon parts of the oil well rig or tools which are hung adjacent to the swivel.

10 In drilling oil wells with the rotary method, it is the common practice to suspend the drill pipe or casing, or other parts which are to be rotated in the well-hole, upon a swivel joint which is in turn suspended upon a suitable bail secured to a hook which is in turn suspended from the crown block tackle.

15 By reason of such suspending mechanism the drill pipe or casing may readily be rotated during the drilling or connecting up operations, while the body of these parts is suspended upon the block and tackle mechanism, permitting the same 20 to be readily raised and lowered. To facilitate the placing of additional sections of drill pipe casing, tubing, etc., in the well, it is the common practice to also hang upon this hook an elevator by which such pipe, tubing or casing is raised 25 and lowered into position in the well, such elevator being swung out of the way of the swivel during the actual drilling operations.

30 The elevator, when swung out of the way, is allowed to merely hang from the hook and allowed to merely rest against the side of the swivel joint. During the drilling operations considerable motion is given to the swivel so that the elevator, instead of resting stationarily against the swivel, is in fact vibrated to a considerable extent, thus 35 causing those parts of the elevator or its bails which contact the swivel, to become worn.

35 It is, therefore, an object of my invention to provide a shock-absorbing rest for the swivel joint which shall act as a buffer or bumper against 40 which the elevator or its bails may rest, such bumper or buffer being constructed to facilitate, or minimize, the vibrations or shocks given to the elevator and thus minimize or eliminate the unnecessary wear of the elevator while it is idle.

45 Another object of the invention is to provide a buffer or bumper upon a drilling swivel which will extend from the swivel to a sufficient distance to constitute a shock-absorbing rest against which either the elevator itself or the bails upon 50 which the elevator is supported may rest and which will absorb the movements of the swivel and the elevator relative to each other to minimize or eliminate wearing thereof.

55 Another object of the invention is to provide a relatively inexpensive buffer or bumper which can be interposed between the elevator and swivel and which may be readily replaced when worn to thus avoid the necessity of replacing worn parts of the swivel or elevator.

60 Other objects and advantages will be apparent

from a study of the following specifications, read in connection with the accompanying drawing, wherein

Figure 1 is a perspective view of a swivel and elevator supported upon a hook and having my shock-absorbing buffer secured upon the swivel to absorb the vibrational shocks of the elevator;

Fig. 2 is a perspective view of a modified form of my buffer which may be employed as a substitute for the buffer shown in Fig. 1; and

Fig. 3 is a horizontal sectional view, taken through the shock-absorber and its mounting means shown in Fig. 2.

As will be readily understood by those skilled in the art of oil well practice, a drill pipe 1 is employed for drilling the well bore which drill pipe is arranged to be rotated by suitable rotary drilling mechanism, not shown. During the drilling operation the drill pipe 1 must be supported above the hole and lowered gradually thereto, as the 20 boring operation proceeds. Also it is necessary to force drilling fluid and washing fluid down through the drill pipe during the drilling operations. To support the drill pipe during the drilling operations and to allow the read injection of 25 the drilling fluid, the drill pipe 1 is secured to a rotating portion 2 of a swivel 3, which swivel is provided with trunnions 4 upon opposite sides thereof to engage the eyes 5 of a bail 6 which passes over a hook 7 supported from the crown 30 block tackle. The drilling fluid is introduced into the upper end 8 of the swivel 3 through a goose-neck 9 to which a flexible hose 10 is coupled.

As will also be understood by those skilled in the art, the swivel 3, being suspended from the 35 hook 7, has considerable lateral motion during the drilling operations, causing it to move through considerable distances as the drill pipe 1 is rotated.

In order to facilitate the insertion of new drill 40 pipe casing, or the like, an elevator 11 is employed adapted, as will be understood by those skilled in the art, to encircle and grip sections of drill pipe or casing to permit the same to be elevated to positions above the drill hole and to be raised or 45 lowered relative thereto. Ordinarily this elevator 11 is suspended from the same hook 7 as supports the swivel 3 and during such times as the elevator is not being actively used it is allowed to hang from the hook 7 and to rest against the 50 swivel 3. The elevator 11 is supported upon a pair of links 12 and 13 having relatively large eyes 14 which engage the hook 7.

The elevator 11 has considerable weight as also has the links 12 and 13, so that when the elevator or the links are allowed to rest against the swivel 3 a condition arises in which any vibration or movement of the elevator 3 tends to vibrate the elevator and its links, causing relatively large masses of materials to be pounded against 55 60

the swivel 3 causing wear either upon the swivel 3 or upon such parts of the elevator or its links as contact the swivel or its supporting ball. In fact the chief cause of wear on the elevators and 5 their links is this vibration and pounding of the elevator and its links against the swivel during the time the drilling operations are taking place. I propose to prevent this unnecessary wear on the elevator and its links and to avoid the wearing 10 of the swivel 3 by providing a relatively inexpensive buffer on the swivel against which the elevator or its links may rest, the buffer being preferably constructed of an elongated body member of some resilient and preferably metallic material. A convenient form of such buffer is 15 illustrated herein as including a cylindrical body member 15 of rubber or similar nonmetallic material, the cylinder being preferably supported upon a pin 16 which extends longitudinally 20 through the cylinder and which pin is preferably secured to the swivel by some means which will dispose the longitudinal axis of the cylindrical buffer body at right angles to the axis of the swivel and spaced laterally of the swivel by such 25 distance as is necessary to prevent metal-to-metal contact between the elevator or its links and the metallic portions of the swivel. That is, I provide a buffer which will be interposed between the 30 swivel and the elevator or other devices which 35 may hang from the hook, the buffer having such dimensions as is necessary to provide a contact area of greater width than the contact portions of the elevator or its appurtenances. In the preferred embodiment of the invention the ends of the pin 16 are carried by brackets 17 which in turn either engage plates 18 or other suitable 40 mounting structures which may in turn be secured at any convenient point to the swivel 3.

As is illustrated particularly in Fig. 2, certain 45 types of swivels 3 are formed with outstanding ears 19 and 20 to constitute shelves or guides against which the elevator 11 or its links may bear to prevent interference between the same and the ball 6 which supports the swivel. Such 50 outstanding ears 19 and 20 may therefore constitute a ready support upon which the plate 18 may be secured.

It will be understood also by those skilled in the art that the primary characteristic of the 55 buffer is that it must comprise a surface, such as the cylinder 15, having a resilient or cushioning effect against which the elevator or its links may contact, and, secondarily, it must be mounted to extend outwardly from the swivel 3 to such 60 distance as will hold the elevator and its links from possible contact with the metallic portion of the swivel or its supporting ball.

While I have illustrated the rubber contact 65 piece as being formed in the shape of a cylinder, other shapes may be employed so long as they furnish a relatively thick wall of rubber or cushioning material which will act to absorb the shocks of movement of the swivel and elevator relative to each other.

While, as is shown in Fig. 2, the elevator may 70 be suspended in such manner that one of the links 13 constitutes the sole contact between the elevator mechanism and the swivel mechanism, certain types of elevator links are arranged so that normally both links contact either the swivel or its bails, thus necessitating a relatively wide

buffer surface which will be sufficiently wide to engage both of the elevator links, and for this purpose I have illustrated a modified form of the device in Figs. 2 and 3 wherein the resilient buffer is formed as two cylinders 15a and 15b mounted 5 upon a pin 16a in alignment with each other. This form of construction permits not only ready replacement of either of the cylinders 15a or 15b, but also permits the interpositioning of a central bracket 17c at the midpoint of the buffer in addition to the end brackets 17a and 17b.

Again, it will be noted in Fig. 2, that the plate 18 of Fig. 1 has been replaced by an angle iron 18a as a mounting device for the buffer to adapt the buffer to be secured to a contact shoe 21 found 15 upon certain types of swivels 3a.

It will therefore be observed that I have provided a buffer or shock-absorbing device which may be readily mounted upon a swivel and which will act as a buffer or cushion upon which the 20 elevator 11 or its bails 12 and 13 may rest, which buffer is relatively inexpensive and may be readily replaced when worn at a cost far less than the cost of replacement of worn elevator links.

While I have shown and described the preferred 25 embodiment of my invention, I do not wish to be limited to any of the details of construction shown herein, except as defined in the appended claims.

I claim:

1. In oil well drilling apparatus wherein two or more devices are supported from a single hook, a buffer interposed between said devices to form cushioning means preventing metal-to-metal contact between the two devices.
2. In oil well drilling apparatus, a swivel, a hook for suspending said swivel, an elevator also suspended from said hook, and a buffer interposed between said elevator and said swivel to prevent metal-to-metal contact between said elevator and 40 said swivel.
3. In oil well drilling apparatus, a swivel, a hook for suspending said swivel, an elevator also suspended from said hook, and a buffer interposed between said elevator and said swivel to 45 prevent metal-to-metal contact between said elevator and said swivel, said buffer comprising a body of resilient material, and means mounting said resilient material upon said swivel to extend outwardly therefrom to such position as to hold 50 said elevator out of metal-to-metal contact with said swivel.
4. In a swivel buffer, a body of resilient material, a plurality of brackets supporting said resilient body upon said swivel in laterally spaced 55 relation thereto.
5. In a buffer for swivels, one or more cylinders of resilient material, means mounting said cylinders upon a plurality of brackets extending laterally from said swivel to secure said resilient 60 body to said swivel in spaced relation thereto.
6. In a buffer for swivels, an elongated body of resilient material, and means for supporting said body on said swivel with the longitudinal axis extending at right angles and in laterally spaced 65 relation to the axis of said swivel including a plurality of brackets extending laterally from said swivel and a pin extending longitudinally through said body and engaging said brackets.

HERBERT C. DYE.
